UNITED STATES PATENT OFFICE.

AUGUSTE DELUBAC, OF VALS-LES-BAINS, FRANCE.

SUBSTITUTE FOR FABRICS, LEATHER, FURS, SPONGES, ETC., FROM COCOONS, AND
METHOD OF MAKING SAME.

1,425,948.

Specification of Letters Patent. Patented Aug. 15, 1922.

No Drawing.

Application filed August 17, 1920. Serial No. 404,253.

(GRANTED UNDER THE PROVISIONS OF THE ACT OF MARCH 3, 1921, 41 STAT. L., 1313.)

To all whom it may concern:

Be it known that I, AUGUSTE DELUBAC, a citizen of the French Republic, residing at Vals-les-Bains, in the Department of Ardeche, and State of France, have invented a Substitute for Fabrics, Leather, Furs, Sponges, Etc., from Cocoons, and Method of Making Same, for which I have filed application in France, December 10, 1915, Patent 10 No. 508,931, of which the following is a specification.

This invention relates to a new industrial product capable of being substituted in wearing apparel for fabrics, leather, furs, etc., and to be used in the place of the above mentioned materials for making clothing, under-clothing, waistcoats, gloves, sleepers, caps, rugs, blankets, sponges, etc.

This new product results from a new application of cocoons of silkworms or the like, which cocoons are used directly for this purpose. The present invention enables the use of any kind of cocoon, either healthy, double or pierced, waste from reeling, or 25 others, before or after scouring, dyeing, etc.

In order to obtain this new product, cocoons which have been used, for instance, cocoons which have been pierced by granulation, are used either as they are or open 30 and are placed next to each other by overlapping or otherwise, and kept together by sewing, gluing or otherwise.

When the cocoons are used open, they may be brushed in order to remove the skins of 35 chrysalides which adhere to them; when they are used entire the skins which they contain are removed by means of a hook.

They are flattened afterwards, after having been moistened, if necessary, by means 40 of a mallet or a press and they may be felted or not, after which they are arranged horizontally one next to the other in one or several plies and their edges overlapping according to a predetermined arrangement 45 such as, for instance, the tiles of a roof or the scales of a fish.

These cocoons thus arranged are afterwards interconnected by means of sewing, gluing, riveting, etc.

50 The finished product may be varnished on one or both faces and it may also be rendered impervious to water or fire proof.

The advantages of the new product are that it is varnished on one side and felted

on the other side; that it is very light, very 55 warm and strong; it allows the passage of the air and of the perspiration through the holes of the sewing through the interstices resulting from the mode of assembling of the cocoon, and especially through the interstices between the threads next to each other of the cocoons which may be of their natural colour or dyed.

When, owing to an abundant perspiration, clothing made of the present product is 65 wet, it is enough to turn it over, the outside part being always dry.

The present substitute of fabric or leather may act as a shock absorber when used in several plies and scoured in the form of cushions on pads, owing to its strength. It may even make an efficient protection against bullets, and splinters. The result is still more so especially if various plies are combined with plates of metal or others.

75 It is obvious that the new product may have various applications and the processes for its manufacture may be varied without departing from the spirit of the invention.

One of the advantages of this product obtained with scoured cocoons is that it is as 80 spongy as sponge and that it has its absorbing capacity.

Having now particularly described and ascertained the nature of my said invention 85 and in what manner the same is to be performed, I declare that what I claim is:—

1. The new fabric herein described consisting of silkworm cocoons or the like flattened out and attached together at their 90 edges.

2. The new fabric herein described consisting of silkworm cocoons or the like flattened out and attached together at their edges, said fabric being varnished on one 95 side and felted on the other.

3. The method herein described for producing a fabric, consisting in flattening out the cocoons of caterpillars, cleaning the flattened cocoons, attaching the flattened cocoons together at their edges to form a fabric and then varnishing the fabric.

100 In testimony whereof I affix my signature, in presence of two witnesses.

AUGUSTE DELUBAC.

Witnesses:

SOULCEOIE MANN,
ROY LEOPOLIE.
